TREADLE SWITCH

Charles N. Merralls and Hubert E. Melchior,
Los Angeles, Calif.

Application December 10, 1947, Serial No. 790,778

10 Claims. (Cl. 200—36)

1

This invention relates generally to treadle switches, and more specifically contemplates unitary switch mechanism and actuating means therefor adapted to control electrical circuits in which the switch is interposed incident to variation in lateral pressure applied thereto.

Treadle switches have heretofore found their widest utility as devices for the control of electrical mechanism adapted to be energized by automotive vehicles. In accordance therewith, the switch is embedded in the street, driveway or roadbed so as to receive the weight of the vehicle passing thereover, and thus close or open a circuit through electrical mechanism of any of various types, as for example apparatus for controlling traffic signals, gates, garage doors, etc.

A common form of treadle switch having numerous advantages in installation and economy of manufacture comprises a pair of wire contacts encased in a common dielectric and normally held by the latter in spaced, vertical alignment. The weight by which the switch is to be actuated, imposed vertically thereon, is effective to displace the dielectric and force the contacts together to complete an electrical circuit through the mechanism controlled thereby. However, as such devices, in the applications indicated, are ordinarily continuously exposed to the elements and are subjected to heavy pressure, their life is limited, and necessary repairs are frequent. A common cause of failure results from the tendency of rubber or other dielectric casing for the contacts to crack or split, permitting the ingress of moisture and corrosive substances. Accordingly, short circuiting is common, and early destruction of the contacts themselves is an inevitable result.

A principal object of the present invention is to largely obviate the deficiencies of the prior art above referred to by the provision of a treadle switch operable in response to lateral pressure upon an elongated mechanical control medium to actuate a switch mechanism completely sealed by means independent of the outer sheathing of the treadle.

More specifically, it is an object hereof to provide a treadle comprising a resilient member sealed within a flexible casing and suspended thereby above a firm support, whereby pressure upon any intermediate reach of the encased member is effective to relieve pressure of one end of the member upon a spring-pressed switch contact, whereby the spring of the switch mechanism is operable to actuate the latter.

2

Another object is to provide in a device of the character above alluded to, a casing for the switch-actuating element, comprising a flexible cable and a resilient sheath adapted to perform the dual function of sealing the cable and actuating element and supporting the latter in an elevated position from which any reach thereof may be depressed to effect the withdrawal from the switch of one end of the actuating element adapted normally to maintain the switch mechanism in predetermined condition.

Another object is to provide a bridge-support for the actuating element, having laterally extending supporting flanges and an intermediate void or air space disposed directly below a centrally located bead through which the actuating element extends, the bottom of the bridge support being substantially flat and sealed to prevent debris from entering the void where it might limit the requisite distortion of the element or damage the lower wall of the bead in response to the pressure thereon.

Still another object is the provision of a switch casing, adapted to be permanently mounted in a position laterally of the treadway, containing a switch having a control member disposed across an opening in the side of the casing through which one end of the tread-actuated element projects, the flexible cable enclosing the actuating element being rigidly secured and sealed to the switch casing to obviate admission into the latter of moisture penetrating the outer sheathing.

Other objects and salient advantages of our invention, such for example as simplicity of construction, economy of manufacture, ease of installation, permanence and durability, as well as positive and permanent sealing of the switch contacts and terminals, susceptibility to standardization with respect to actuating weight or pressure and compactness, will be apparent to those of skill in the art upon an examination of the following description read in the light of the accompanying drawings, in which:

Fig. 1 is a longitudinal vertical section, partially in elevation, through a treadle switch embodying my invention;

Fig. 2 is a plan view, partially broken away, of the device shown in Fig. 1;

Fig. 3 is a broken side elevation, partially in section, depicting the effect of the weight of an automotive vehicle upon the actuating assembly; and

Fig. 4 is a sectional view taken on line 4—4 of Fig. 1.

Referring to the drawings more in detail, the numerals of which indicate similar parts throughout the several views, 5 designates a flat casing, rectangular in plan, and divided by a partition 6, offset toward one end thereof. The larger compartment 7 of casing 5 forms a receptacle for electrical conductors 8 and 9 fed into the casing through a suitable conduit (not shown) for which a circular opening 10 is provided in the bottom of the receptacle. The wires 8 and 9 are connected to a pair of terminals 11 mounted upon the transverse partition 6 through which wires an electrical circuit may be completed and broken by means of a switch 12 of conventional construction carried within the smaller section of the casing. The switch mechanism 12 is sealed permanently within the smaller section 13 by a coverplate 14. Similarly, the terminals 11 of switch 12, extending into the larger section 7 of the casing, are sealed against moisture by a suitable insulating material with which the section 7 is filled after connection of the switch in the circuit at the point of its intended use.

Switch 12 is of the normally closed type and is held open by lateral pressure, applied by means hereinafter described, upon a resilient plate 15 forming a part of the switch and attached permanently to one side of the switch body so as to extend adjacent and substantially parallel to the end 16 of casing 5.

Projecting laterally from the center of, and forming a right angle with the end 16 of the casing, is a tube 17. The bore of tube 17 opens to the interior of the switch housing 7, and loosely accommodates one end of a flexible wire or rod 18 adapted to normally bear against the resilient plate 15 of the switch so as to hold the latter open in response to its pressure thereagainst. The length of rod 18 varies in specific embodiments depending upon the ground area over which switch control is required. For example, where the device is to be actuated by a motor vehicle in conjunction with mechanism for opening and/or closing a garage door, gate and the like, rod 18 is of a length to extend transversely across the driveway, roadbed or garage floor a distance sufficient to insure that one or both wheels at one side of the vehicle pass over the rod.

The rod is encased within a flexible cable 19, one end of which is fitted into and secured rigidly in the outer end of tube 17 with its opposite end terminating slightly short of the opposite end of the rod. The outer end of cable 19 is sealed around the rod 18 by a weld or braze, as indicated at 20, which is effective to resist relative longitudinal movement between the cable and rod ends. The extreme outer end of rod 18 is beaded as at 21 to form an annular constriction between the end of cable 19 and the bead 21 for a purpose later referred to. The cable is not normally longitudinally compressible, and, being firmly attached to rod 18 at the outer end of the latter and to the tube 17 of the casing 5, normally holds the end of rod 18, projecting into the casing, firmly in contact with the resilient plate 15 of the switch, the pressure of the rod, when the rod and cable are straight, being sufficient to maintain the switch open.

The entire cable 19, tube 17 and the beaded tip 21 of rod 18 are encased within a treadle-sheath 22, composed of rubber or other resilient mate-

rial. Sheath 22 comprises an elongated flat bottomed base section having formed integrally therewith an upstanding bead 23 through which a hole 24 extends for projection of the cable 19. Hole 24 is spaced from the bottom of sheath 22 a distance substantially corresponding to the distance between tube 17 and bottom of casing 5 so as to support the cable 19 and rod 18 in a horizontal plane when the casing 5 and sheath 22 are correspondingly positioned.

The laterally-projecting sides of the bottom of sheath 22 afford a means for clamping the latter within a suitable frame (not shown) with which conventional treadle switches are commonly equipped, so as to support the upper arc of the bead above the adjoining portions of the frame.

It will be observed that as tube 17 is sealed to the body of casing 5, and cable 19 is similarly sealed to the end of tube 17 and to outer end of rod 18, no moisture can enter the switch casing through the bores of the cable and tube. However, in order to avoid corrosion of the cable, the end of sheath 22 enclosing the tube 17 is vulcanized to the end wall 16 of the casing and its opposite end completely encloses the beaded tip 21 of rod 18 as indicated in Fig. 1. The restriction formed between bead 21 and the cable end is thus filled with the material of which the sheath is formed so as to insure an effective seal and to resiliently resist movement of the outer end of the rod 18 toward the switch casing upon flexing of an intermediate reach of the cable and rod in accordance with the operation of the device as is hereinafter more fully described.

The sheath 22 includes a flat air chamber 25 extending throughout its length below cable 19. The air chamber 25 is sealed at each end by a plug 26 vulcanized therein, so as to provide a void in the material into which cable 19 and rod 18 may be depressed upon the application of pressure to any intermediate reach of the treadle assembly. It will be appreciated that a portion 27 of sheath 22 immediately below cable 19 is quite thin to facilitate the depression of the latter while preserving the sealed condition of the cable. Similarly the lower wall 28 or bottom of air chamber 25 is imperforate to preclude the entry of any substances below cable 19 which might interfere with the effective flexing of the rod in response to pressure upon the treadle assembly. The completely sealed chamber 25 is of a width equal to or slightly greater than the width of bead 23, whereby an entire reach of the bead may be depressed incident to pressure upon the upper arc thereof, so as to minimize distortion of bead 23 incident to obtaining the required flexure of the rod.

The operation and utility of the device is further briefly described as follows: The unit is preferably installed in the roadbed, floor, driveway or the like with the switch casing 5 disposed at the edge of the treadway where it is protected against damage by the vehicles or other means by which the switch is to be actuated. The treadle sheath 22, with encased cable 19 and rod 18, suitably mounted within a frame adapted to maintain its position, is arranged to project across the treadway a sufficient distance to assure reception of the weight of the vehicle, the upper arc of bead 23 extending slightly above the plane of the treadway.

The weight of the vehicle moving across the treadle depresses the section of the sheath bead 23 and corresponding reach of the cable 19 and rod 18, encased thereby, into the chamber 25.

The bending of the treadle assembly tends to cause a contraction of the end of the rod 18 projecting into the switch casing 13. This movement of the rod end is effected as a result of several independent actions of the parts of the treadle, as about to be described, each of which are capable of causing the required movement of the rod end, but in the embodiment illustrated all cooperate to actuate the switch 12. With rod 18 disposed within cable 19, flexing of these elements tends to retract both ends of both the rod and cable, but, due to the differences in radii of the curves imposed upon these elements, the ends of the rod tend to be retracted to a greater extent. However, as the outer end of the rod is firmly held by the normally incompressible cable, this greater retraction of the rod is concentrated at the end thereof which extends into contact with the switch plate 15.

Moreover, as above indicated, one end of cable 19 is rigidly attached to the end of tube 17, and the opposite end of the cable is mounted firmly in the rubber sheathing, thus substantial longitudinal movement of one of the cable ends is firmly resisted while the other end is resiliently resisted. Being flexible and slightly extensible, however, the cable largely absorbs and localizes the distortion resulting from the weight of the vehicle thereon. The resilience of the material of which the sheathing 22 is formed, while reinforcing the position of the outer end of the cable 19 as immediately above described, permits slight contraction of the outer end of the cable upon flexure of an intermediate reach thereof. The rod 18, however, being secured at only its outer end, is permitted by the cable 19 and sheath 22 insufficient longitudinal movement to absorb the lateral displacement of its intermediate reach in response to substantial pressure thereon. Accordingly, the opposite free end of rod 18 extending into the switch casing 5 is retracted into the bore of tube 17, thus relieving pressure upon switch plate 15 and permitting the switch to close in response to the urge of resilient means forming a part of the switch mechanism.

Upon relaxation of the pressure on the treadle assembly, the resilience of the rod 18, cable 19 and sheath 22 compels the return of these elements to their original position, again projecting the free end of the rod against the switch plate 15 so as to re-open the circuit. The momentary closing of the switch 12 permits its utility for control of a circuit through a relay (not shown) by which the primary circuit through the electrical mechanism to be actuated is controlled.

It will thus be seen that we have provided a flexible treadle adapted to be distorted in response to pressure thereon so as to shift one end of an element of the treadle with respect to laterally-disposed switch mechanism with which it is normally engaged, for actuating the latter, the arrangement of the elements being such as to assure complete protection of the metal components of the treadle from corrosion and of the switch mechanism per se from moisture.

While we have shown a preferred embodiment of the invention, it will be appreciated that the device specifically alluded to is merely illustrative of certain essential features which may be incorporated in many forms and arrangements within the skill of those in the art, and that the outer end of the rod may extend slidably through the corresponding end of the cable for attachment to a suitable mounting, that the outer end

of the cable may be similarly mounted and absorb the lateral pressure against its intermediate portion incident solely to its inherent resilience, that the cable may be movable through the sheath in response to lateral pressure thereagainst independent of the rod, and that where occasion requires a single treadle may be employed to mechanically control the operation of a pair of switches located at opposite ends of the treadle assembly, all without departing from the spirit of our invention as defined in the appended claims.

What we claim and desire to secure by Letters Patent is:

15. In a treadle switch mechanism, a pair of flexible members coaxially disposed, means to secure corresponding ends of said members rigidly together to resist relative longitudinal movement therebetween, a casing, and means to secure the opposite end of the outer flexible member to said casing, the opposite end of said inner member extending into said casing and movable longitudinally relative to the latter in response to flexing of an intermediate reach of said inner member.
20. In a treadle switch mechanism, a flexible tubular member and a flexible elongated member coaxially disposed and having one pair of corresponding ends thereof connected rigidly together, the opposite ends of said members being movable longitudinally with respect to one another, the outer member being composed of non-compressible material to resist retraction of the end of said inner member connected thereto incident to joint flexing of said members whereby lateral displacement of an intermediate reach of said members is effective to retract the relatively movable end of said inner member, and means to hermetically seal the end of said outer member that is connected to said inner member.
25. In a treadle switch mechanism, a casing having an opening in one end thereof but otherwise hermetically sealed, a switch in said casing, a treadle member extending reciprocably into said casing and engaging said switch, and a flexible, non-contractile tube encasing said treadle member having one end sealed to said casing and the opposite end sealed to the corresponding outer end of said member.
30. In a treadle switch mechanism, a switch, a flexible treadle member having one end engageable with said switch to actuate the latter in response to longitudinal movement, and means including a flexible sheath for said member engaged rigidly with the opposite outer end of said member to resist relative displacement of the latter outer corresponding ends of the member and sheath whereby flexing of said member and sheath is operable to retract said switch-engaged end of said member.
35. In a treadle switch mechanism, a switch, a treadle member having one end engageable with said switch to actuate the latter in response to longitudinal movement of the member, a tube encasing said treadle member, and means to resist longitudinal movement of the ends of said tube, the switch-engaging end of said treadle member being slidably through the corresponding end of said tube, and the opposite end of said treadle member being secured to said tube.
40. In a treadle switch mechanism, a switch, a treadle member having one end engageable with said switch to actuate the latter in response to longitudinal movement of the member, a tube encasing said treadle member, and means to resist longitudinal movement of the ends of said tube, the switch-engaging end of said treadle member being slidably through the corresponding end of said tube, and the opposite end of said treadle member being secured to said tube.
45. In a treadle switch mechanism, a switch, a treadle member having one end engageable with said switch to actuate the latter in response to longitudinal movement of the member, a tube encasing said treadle member, and means to resist longitudinal movement of the ends of said tube, the switch-engaging end of said treadle member being slidably through the corresponding end of said tube, and the opposite end of said treadle member being secured to said tube.
50. In a treadle switch mechanism, a switch, a treadle member having one end engageable with said switch to actuate the latter in response to longitudinal movement of the member, a tube encasing said treadle member, and means to resist longitudinal movement of the ends of said tube, the switch-engaging end of said treadle member being slidably through the corresponding end of said tube, and the opposite end of said treadle member being secured to said tube.
55. In a treadle switch mechanism, a switch, a treadle member having one end engageable with said switch to actuate the latter in response to longitudinal movement of the member, a tube encasing said treadle member, and means to resist longitudinal movement of the ends of said tube, the switch-engaging end of said treadle member being slidably through the corresponding end of said tube, and the opposite end of said treadle member being secured to said tube.
60. In a treadle switch mechanism, a switch, a treadle member having one end engageable with said switch to actuate the latter in response to longitudinal movement of the member, a tube encasing said treadle member, and means to resist longitudinal movement of the ends of said tube, the switch-engaging end of said treadle member being slidably through the corresponding end of said tube, and the opposite end of said treadle member being secured to said tube.
65. In a treadle switch mechanism, a switch, a treadle member having one end engageable with said switch to actuate the latter in response to longitudinal movement of the member, a tube encasing said treadle member, and means to resist longitudinal movement of the ends of said tube, the switch-engaging end of said treadle member being slidably through the corresponding end of said tube, and the opposite end of said treadle member being secured to said tube.
70. In a treadle switch mechanism, a switch, a treadle member having one end engageable with said switch to actuate the latter in response to longitudinal movement of the member, a tube encasing said treadle member, and means to resist longitudinal movement of the ends of said tube, the switch-engaging end of said treadle member being slidably through the corresponding end of said tube, and the opposite end of said treadle member being secured to said tube.
75. In a treadle switch mechanism, a switch, a treadle member having one end engageable with said switch to actuate the latter in response to longitudinal movement of the member, a tube encasing said treadle member, and means to resist longitudinal movement of the ends of said tube, the switch-engaging end of said treadle member being slidably through the corresponding end of said tube, and the opposite end of said treadle member being secured to said tube.

the end of said tube encasing the switch-engaging end of said treadle member against movement relative to said switch, and means to resiliently resist longitudinal movement of the opposite end of said tube, said treadle member having its switch-engaging end slidably in said tube and its opposite end secured firmly to the corresponding end of said tube, and means to hermetically seal the last-named end of said tube.

7. In a treadle switch mechanism, a casing, a switch sealed within said casing, a flexible tube connected to one side of, and opening into, said casing adjacent said switch, and a flexible treadle member within said tube having one end projecting into said casing to actuate said switch in response to longitudinal movement thereof, the outer end of said tube being sealed and secured to said treadle member to resist relative longitudinal movement between the outer end of said treadle member and said tube.

8. In a treadle switch mechanism, a switch, a casing for said switch having an opening therein, a flexible treadle member having one end extending into said casing through said opening to actuate said switch in response to longitudinal movement of said member, means to secure the opposite end of said member against substantial longitudinal movement relative to said switch whereby flexing of said member is effective to retract said switch-actuating end of said member, and means to encase said member, and means to hermetically seal said last-named encasing means to said casing around said opening.

9. In a switch mechanism, a switch casing, a switch in said casing, an elongated block of resilient and compressible material having one end hermetically sealed to one side of said casing, a flexible, non-contractile tube in said block and having one end secured rigidly to said side of

the casing, an elongated, switch-actuating member extending loosely through said tube, having one end projecting into said casing to actuate said switch in response to longitudinal movement of said last named end of said member, and the other end of said member secured rigidly to the outer end of said tube, said casing and said block coacting in hermetically sealing said switch and said switch-actuating member.

10. In a switch mechanism, a switch casing, a switch in said casing, an elongated block of resilient and compressible material having one end hermetically sealed to one side of said casing, a flexible, non-contractile tube in said block and having one end secured rigidly to said side of the casing, an elongated, switch-actuating member extending loosely through said tube, having one end projecting into said casing to actuate said switch in response to longitudinal movement of said last named end of said member, and the other end of said member secured rigidly to the outer end of said tube, said casing and said block coacting in hermetically sealing said switch and said switch-actuating member, the outer ends of said tube and member being secured within and to said block to resiliently resist movement of said ends relative to the casing.
